LEG FOR BATH TUBS, &c.

Patented July 6, 1886.

No. 16,784.

UNITED STATES PATENT OFFICE.

WILLIAM C. PEET, OF NEW YORK, N. Y., ASSIGNOR TO THE J. L. MOTT
IRON WORKS, OF SAME PLACE.

DESIGN FOR A LEG FOR BATH-TUBS, &c.

SPECIFICATION forming part of Design No. 16,784, dated July 6, 1886.

Application filed May 7, 1886. Serial No. 201,492. Term of patent 14 years.

To all whom it may concern:

Be it known that I, WILLIAM C. PEET, of the city and State of New York, have invented a Design for the Legs of Bath-Tubs, Stoves, &c., of which the following is a specification. The design of this leg is represented in the accompanying photograph. The ball A at the base is shown as below the claws B, and the leg is curved laterally from the claws and rises above the same, spreading out with a compound curved outline at C, and the face of the leg is rounding, as represented, and the surface is ornamented by moldings at D, scroll ornaments at E, and leaflet ornaments at F, and there are astragal ornaments at P,

the whole forming a design having a neat and artistic appearance.

I claim--

The design for the leg of bath-tubs, &c., herein shown and described, consisting in the ball and claws at the lower end of the leg, the curved and rounded upper portion of the leg, and the scrolls, leaflet ornament, and moldings, substantially as represented.

Signed by me this 1st day of May, A. D. 25
1886.

WM. C. PEET.
